OUTDOOR SNACK WAGON

James C. Cassie, Mount Prospect, Ill., assignor to Steel Sash Service, Inc., a corporation of Illinois

Filed Aug. 7, 1964, Ser. No. 81,191

Term of patent 14 years

(Cl. D13—1)

Fig. 1.

Fig. 2.

Fig. 3.

FIGURE 1 is a side elevation of an outdoor snack wagon, according to my invention;

FIGURE 2 is a rear elevation of the wagon of FIGURE 1; and

FIGURE 3 is a perspective view of the wagon of FIGURE 1.

I claim:

The ornamental design for an outdoor snack wagon, as shown.
